UNITED STATES PATENT OFFICE.

FRANK C. ACKER, OF IONIA, MICHIGAN.

CRACKER-CABINET.

SPECIFICATION forming part of Letters Patent No. 472,020, dated April 5, 1892.

Application filed June 8, 1891. Serial No. 395,601. (No model.)

To all whom it may concern:

Be it known that I, FRANK C. ACKER, a citizen of the United States, residing at Ionia, in the county of Ionia and State of Michigan, have 5 invented certain new and useful Improvements in Cracker-Cabinets; and I do hereby declare the following to be a full, clear, and exact description of the invention, such as will enable others skilled in the art to which it app- 10 pertains to make and use the same.

My invention relates to improvements in devices for storing, preserving, and handling crackers and other like articles; and its object is to provide a device for such purposes hav- 15 ing certain new and useful features herein- after more fully described, and particularly pointed out in the claims, reference being had to the accompanying drawings, in which—

Figure 1 is a front elevation of a device embodying my invention, with a part broken away to show the construction; Fig. 2, a vertical section of the same on the line xx of Fig. 1, and Fig. 3 a horizontal section of the same on the line yy .

Like letters refer to like parts in each of the figures.

A represents a case or box, of suitable form, having an overhanging front portion A', a forwardly-inclined top having doors B and B' 20 opening into A and A', respectively, and forwardly-inclined back portions U and T. In the lower part of A' is arranged, in an opening at one side, a removable scoop H, beneath which is a lateral extension H' of A' to retain such of the contents of the same as may 25 follow the scoop when withdrawn, and at the other side thereof is a semi-cylindrical pocket D, one-half of the bottom of which consists of a quadrantal valve E, of slightly-less radius 30 than the stationary part of said bottom, over which stationary part it is arranged to move by being pivoted to a shaft F', journaled in the axis of said pocket, which shaft is provided with a crank F for opening the valve E 40 and a spring F'' for closing the same.

C is a glass plate inserted in the front of A', through which the contents may be observed, and G is a spout into which the valve E opens to discharge the contents of A'.

Within the case A is the grated floor M, hinged at its front edge to the front of the

same at the bottom of the opening therefrom into A' and about on a level with the top of the pocket D and scoop H. To the rear or movable side of said floor are attached straps 55 O, of webbing or other suitable material, which extend upward and rearward to the top of A, pass over a roll P, journaled therein, and thence downward to near the bottom and at the rear of the same, and are wound upon 60 a roll P', having a crank S to turn it, and provided with a ratchet Q and pawl R to retain it in position. Said straps have attached a series of transverse parallel bars N, which, together with M, constitute a movable grated 65 bottom to secure the crackers and suspend them within A.

J is a lamp or other suitable heater having its chimney J' surrounded by a chamber K, within which said chimney connects to a hot-air 70 pipe L, which extends horizontally across the interior of A beneath the floor M, and thence returned to K, where it is extended upward at L' into the open air. A steam-coil or any other suitable heater may be substituted for 75 this latter device when convenient.

I is a door opening into the lower part of A to remove the dust and particles that pass through said bottom.

The operation of my device is as follows: 80 The straps O are first unwound from P', allowing the rear of the grated floor to descend to the bottom of the case A. The stock of crackers can then be poured in through the door B, and as the straps P' are from time to 85 time wound upon the roll P' the bottom M and the slats N rise and discharge said crackers into A', whence they are removed either by the scoop H or valve E, as most convenient, any residue after weighing being returned 90 by the door B'. In the meantime the smaller particles and flour-dust pass through the bottom M and slats N and fall to the bottom, whence they may be removed by the door I, the inclined back reducing the area of the 95 bottom and bringing them nearer the front. The glass C serves to display the goods, and the heater-pipe L maintains their condition of dryness, thus preserving them in good order for use.

What I claim is—

1. In a cracker-cabinet, a closed chamber

having a perforated and vertically-movable bottom, a heater beneath the same, an adjacent chamber into which the crackers are discharged, and mechanism for removing said crackers from the latter chamber, substantially as described.

2. In a cracker-cabinet, a storage-chamber having an opening in one side and a grated bottom hinged at one side thereof and beneath said opening-straps attached to the movable side of said bottom, having parallel transverse slats attached, and a roll upon which said straps are wound, said roll having a crank and a ratchet-wheel and pawl, substantially as described.

3. In a cracker-cabinet, a closed chamber having a perforated and vertically-movable bottom, a heater beneath the same, an adjacent chamber having a semi-cylindrical bottom and a discharge-opening in the same, and

a quadrantal valve closing said opening, substantially as described.

4. In a cracker-cabinet, a storage-chamber having a grated bottom pivoted at one side and vertically movable at the other, a heater beneath the same, a chamber into which the crackers are discharged as said bottom rises, said chamber having a semi-cylindrical pocket provided with a segmental valve and a discharge-spout and also having a laterally-prolonged floor, a lateral opening, and a scoop adapted to close said opening and to be removed therefrom, substantially as described.

In testimony whereof I affix my signature in presence of two witnesses.

FRANK C. ACKER.
